UNITED STATES PATENT OFFICE.

ANTON ANFINSON, OF WAKONDA, SOUTH DAKOTA.

ROADWAY.

1,353,446.

Specification of Letters Patent. Patented Sept. 21, 1920.

Application filed May 8, 1919. Serial No. 295,580.

To all whom it may concern:

Be it known that I, ANTON ANFINSON, a citizen of the United States, and a resident of Wakonda, in the county of Clay 5 and State of South Dakota, have invented certain new and useful Improvements in Roadways, of which the following is a specification.

My invention is an improvement in road 10 ways, and has for its object to provide mechanism for use in connection with ordinary country highways, for converting said highways at small expense and in a minimum of time into metaled road ways, to 15 provide relatively narrow tracks of plastic material capable of hardening, such for instance as concrete.

In the drawings:

Figure 1 is a plan view showing an arrangement of double track,

Fig. 2 is a similar view showing an arrangement of single track,

Figs. 3 and 6 are sections on the lines 3—3 and 6—6 of Fig. 1,

Fig. 4 is a section on the line 4—4 of Fig. 2,

Fig. 5 is an enlarged section of one of the track ways.

In the embodiment of the invention 30 shown in Fig. 1 the road way 1 which is crowned or arranged transversely in the usual manner, and provided with the drainage ditches or gutters 2 at each side as at the center of the crown thereof four relatively narrow track ways 3. These track 35 ways are spaced apart from each other a distance corresponding to the standard gage of the vehicles, so that the wheels of a vehicle may run upon two adjacent track ways 40 to support said wheels out of contact with the soil.

In the present instance the spacing of the four track ways is the same, so that a vehicle may run upon any two adjacent 45 track ways. It is obvious however that the two pairs of track ways might be spaced closer together or farther apart if desired.

At road crossings the adjacent track ways of the intersecting roads have their adjacent sides connected by curving lines 4, and the entire space between these four lines 4 is paved with concrete indicated at 5. Thus the four tracks of the two intersecting roads are practically continuous. A vehicle for

instance on the two right hand tracks of 55 Fig. 1 moving toward the bottom of the sheet may turn curvingly on to the two right tracks at the left of the sheet. Since only enough concrete is used to make a relatively narrow track way for each wheel, 60 except at road intersections it will be obvious that the cost of a road way constructed in accordance with the invention will be very much less than were it necessary to pave the entire width of the tread 65 portion of the road.

In Fig. 2 is shown a single track arrangement, each road way having two tracks 6 properly spaced with respect to each other. At road intersections the four relatively narrow track ways are connected by 70 the paving 7 which is of approximately square outline, having however its sides concave.

Referring to Fig. 6 it will be observed 75 that the upper face of each track way is concave, that is it is hollowed out or guttered from side to side to provide trough shaped depression 8 in the other surface of the track way. This assists in retaining 80 the wheels in the track way. Each track way may be reinforced in any suitable manner, as for instance by series of reinforcing rods 9 which are arranged transversely of the track way at suitable intervals, 85 and also by longitudinally extending reinforcing rods 10, any suitable number and arrangement being used. In practice expansion joints will be provided, the said joints being arranged at desired intervals, 90 as for instance every 50 to 100 ft. according to locality and to the usage to which the road will be exposed.

The improved road way will accommodate not only motor vehicles, but horse 95 drawn vehicles as well, and is especially adapted for the use of horses, since the horse has the path way of soil on which to travel. As is known, hard pavements are very trying on the hoofs of horses. With 100 the present construction the horse travels on the ground.

With the single track construction, suitable passing points might be provided if desired, in the nature of switches. It will 105 be obvious that while a firm and solid wheel base is provided, the expense will be much less, both for material and labor than where

the entire road way is made solidly concrete.

I claim:

5 In combination, a plurality of trackways arranged in intersecting relation and terminating short of actual intersection, each trackway being formed of a plurality of

spaced parallel bodies of plastic material embedded within the ground and each concaved at its upper face in cross section, and 10 a smooth pavement connecting the ends of the trackways.

ANTON ANFINSON.
